UNITED STATES PATENT OFFICE.

MOSES W. KIDDER, OF LINCOLN, MASSACHUSETTS.

SCHOOL-DESK.

SPECIFICATION forming part of Letters Patent No. 388,417, dated August 28, 1888.

Application filed February 14, 1888. Serial No. 264,010. (No model.)

To all whom it may concern:

Be it known that I, MOSES W. KIDDER, a citizen of the United States, and a resident of Lincoln, in the county of Middlesex and State 5 of Massachusetts, have invented new and useful Improvements in School-Desks, of which the following, taken in connection with the accompanying drawings, is a specification.

Of the accompanying drawings, forming a 10 part of this specification, Figure 1 is a plan showing the top of a desk closed down, a portion being cut away. Fig. 2 is a cross-section on the line A B of Fig. 1, with top of desk closed down. Fig. 3 is a like section showing 15 the desk open or the top raised to an angle.

Similar letters refer to similar parts throughout the several views.

This invention consists in certain improvements in school-desks, whereby they may be 20 made more suitable for the various uses required of them in reading and writing.

The object of this invention is to correct a manifest fault of position of pupils in school when using the desk in reading or study. As 25 the book lies upon the ordinary school writing-desk, it necessitates a malposition of the body in bending forward over the book, and the eye, falling at an angle upon the page, gradually but certainly ultimates in deformity 30 and consequent astigmatism and myopia.

In the construction of a school-desk embodying my improvements I provide supports in any of the ordinary forms in common use. Upon these the floor or bottom of the desk 35 rests and is firmly secured. Fixed to and rising from this floor vertically upon three sides are the right and left hand sides D and the back side of the desk. Extending across from one side to the other and projecting a little 40 over the vertical sides D, and covering the top edge of the back side, is immovably fixed a part of the top T, about five inches wide, in which is placed the ink-well. I next provide the movable or adjustable top t, of the same 45 length as the fixed portion T and about seven inches wide. Upon the under side of this movable top t, near the front edge, and projecting downwardly at a right angle to the under surface and parallel to the ends of the 50 desk, are fixed the combined "friction-plate hinges" a, one near each end and at such a

distance from each other that when the movable top t is in its position the outer faces of the friction-plate hinges a fit nicely against the inner surfaces of the two vertical sides D of the desk, against which the said friction-hinge plates are pressed by the friction-clamps b, provided for that purpose, and secured on the inner surface of the vertical sides D of the desk by adjustable screws b'. The friction hinge 60 plates a turn upon center bolts, a', which pass through them and the vertical sides D near the front edge of the desk. I next provide a ledge, c, of wood, of the same length as the top t, about three-fourths of an inch thick by one 65 and a half inch wide. To the under edge of this ledge c, near each end, is rigidly fixed a lever, C, about seven inches long, parallel to each other in the same direction and at right 70 angles to the ledge, which rests upon one end of the levers. This ledge is next placed in its position against the front edge of the movable top t, the levers C passing backwardly under, and are loosely attached by one end to the under surface of the movable top t, thus allowing 75 limited motion of the ledge c to project or re-cede. These levers C, at each side supporting the ledge c, rest upon cam pins or studs d, fixed on the inner surface of the vertical sides D of the desk about one inch nearer the front 80 edge of the desk than the center bolts, a', upon which the friction-plate hinges a turn.

Above each lever C is provided a spring, e, which, acting against the under side of the movable top t, together with the gravitation 85 of the ledge and levers, holds the levers down upon the cam pins or studs d.

Having described the construction of my improved desk, I will indicate its operation.

When used for a writing-desk, the adjustable top t is placed in the position shown in Fig. 2, the ledge c being flush with the top t. On raising the top t on its hinges a, as shown in Fig. 3, thus converting it into a reading-desk, the friction-hinge plates a, pressed 90 against the inner surface of the vertical sides D of the desk by the friction-clamps b, enable the top to be arrested and held at any desired angle without any turning of screws or liability of falling from its position. As the top t 95 is being raised to an angle approaching a vertical, the levers C, resting upon the cam-pins

d, are not permitted to fall concentrically with the adjacent edge of the top *t*, and the ledge *c*, resting upon the levers *C*, is automatically projected from the line of the upper surface of 5 the adjustable top *t* to prevent books or slates from sliding from the desk. As the position as shown in Fig. 2 is resumed, the levers *C*, resting upon the cam-pins *d*, by action of the springs *e* or gravitation of the ledge and levers, or both, cause the ledge to recede, so that it is again flush with the upper surface of the top *t*.

I am also aware that prior to my invention herein described curved friction arms or bars 15 have been used to stay movable desk-tops in desired positions, in combination with and attached to an intermediate lid or frame, as shown in United States Patent No. 226,842; also, as shown running down toward the floor 20 through the desk in United States Patent No. 340,847; also, friction-tight joints or hinges by which the desk-top is hinged to levers, as claimed and shown in United States Patents Nos. 248,043 and 329,175, where the top rotates 25 upon trunnions between upright standards; also, in United States Patent No. 163,605, the notched hinge-plate near the back side of the desk.

I am also aware of the adjustable ledge 30 shown in United States Patent No. 163,605, which is partially rotary and not automatic; also, the ledge shown in United States Patents Nos. 340,847 and 248,043, which are automatic. In the former the top is hinged directly to the 35 ledge, which is fixed at each end to the sides of the desk and is immovable, and in the latter the top is hinged near the front edge to two levers, which support the cylindroid ledge; also, in United States Patent No. 329,175, in 40 which is presented a reversible table with a fixed ledge upon one side and none on the other, said table turning upon trunnions resting in upright standards at each side.

In the above references in Nos. 329,175 and 45 163,605 the usual space provided for books is

wholly sacrificed. In Nos. 226,842 and 340,847 the same space is largely encumbered by the mechanism, while in No. 248,043, and as shown in this specification, the said space is wholly economized.

50

It will be noticed that in none of the above references do the tops of the desks, which turn upon hinges near the front edge, hinge upon the inner surface of the vertical sides of the desk, as shown and described in this specification. 55

It will also be noticed that in none of the above references cited do the friction plates or arms depend upon frictional contact with the sides of the desk, but upon dogs or springs, as 60 shown, entirely unlike the mechanism herein shown and described.

What I claim as new, and wish to secure by Letters Patent, is—

1. In a school desk, the combination of the 65 adjustable top, the sector-shaped hinge-plates secured to the under side of said top and turning upon a pin at the center, the friction-clamp consisting of a bar secured at one end to the side of the desk and bearing at its other end 70 upon the hinge-plates, and the adjusting-screw passing through the clamp-bar and engaging the side of the desk, as and for the purpose set forth.

2. In a school-desk, the combination, with a 75 hinged desk-top, of one or more levers secured to the under side of the desk-top, a ledge normally supported by said levers in position flush with the desk-top, and a stud on the desk eccentric to the pivot and adapted to engage 80 the levers to throw the ledge upward when the desk-top is raised, substantially as set forth.

In testimony whereof I have signed my name to this specification, in the presence of two subscribing witnesses, on this 10th day of February, 85 A. D. 1888.

MOSES W. KIDDER.
